LIQUID GRAVITOMETER

George S. Binckley, Los Angeles, Calif., assignor,
by decree of court and mesne assignments, to
Sydney William Binckley, as trustee

Application August 4, 1940, Serial No. 351,358

8 Claims. (Cl. 265—44)

This invention relates to improvements in liquid gravitometers.

An object of this invention is to provide means through which the specific gravity of a continuously flowing sample of liquid may be indicated or recorded.

A further object of this invention is to provide means through which a continuously flowing sample of liquid, the specific gravity of which is to be indicated or recorded, may be passed through the instrument under pressure.

Another object of this invention is to provide means through which the action of the instrument in indicating or recording the specific gravity of a continuously flowing sample may be employed to control the specific gravity of the liquid in question or to exercise control over processes which depend for their correct functioning upon the specific gravity of the liquid involved.

Another object of this invention is to provide means through which changes in the temperature of the continuously flowing sample of liquid are automatically compensated so that the indication or record as made shall be the specific gravity of the liquid as of a standard temperature—say 60° F.

Other objects of the invention will appear as the description thereof proceeds.

The invention comprises a liquid gravitometer which is simple of construction, inexpensive in cost of manufacture, and generally superior to gravitometers now known to the inventor, in that it is fool-proof and capable of working over a long duration of time without the attention of an attendant.

With the above named objects and others in view, the invention consists in the novel and useful provision, formation, construction, association, and relative arrangement of parts, members and features, all as depicted in a certain embodiment in the accompanying drawings, described generally, and more particularly pointed out in the claims.

In the drawings:

Figure 1 is a schematic diagram of the instrumentalities entering into the construction of the liquid gravitometer, with certain parts broken away and in section,

Figure 2 is an enlarged sectional view on the line 2—2 of Figure 1,

Figure 3 is an enlarged sectional view on the line 3—3 of Figure 1, and,

Figure 4 is an enlarged sectional view on the line 4—4 of Figure 1.

Referring now to the drawings, the improved

liquid gravitometer includes a base 1 having mounted thereon a pedestal or standard 2 as by means 3. A cross piece 4 is secured to the top of the pedestal or standard by means 5, and this cross piece has secured thereto and depending therefrom a knife-edged member 6. The knife-edged member is adapted to support a beam 7, the bearing 8 of said beam resting upon the knife edge 9 of the member 6. This provides the fulcrum for the beam. One end of the beam is provided with a bearing 10. A knife-edged member 11 has the knife edge thereof supported by the bearing 10 and the member 11 in turn is swingingly secured by means 13 to a cross head carrying a pair of suspension links 12. A screw cap 14 has the threads thereof in engagement with the threads of a fitting 15. The fitting 15 in turn is threaded to an annular nut 16, the nut being fastened by welding or otherwise to a bulb 17. In the present instance, the bulb is in the form of a hollow ball with the links 12 diametrically loosely pinned to the ball.

Diametrically opposite the fitting 15 and secured to the wall of the bulb is a further fitting 18 provided with a screw cap 19. Access to the interior of the bulb may be effected by removing the cap 19. Depending from the fitting 15 and diametrically disposed within the bulb is a tube 20. The lower end of said tube is spaced slightly above the shank of the cap 19 so as to permit fluid ingress. The opposite end of the tube has egress in the space 21 of the fitting 15. The fitting 15 is provided with one or more transverse bores 22 which communicate with the upper portion of the bulb 17 and with the space 21. The beam 7 carries an adjustable weight 23 for the purpose of counter-balancing the weight of the bulb and its fittings.

A block 24 is secured to the base 1 in any appropriate manner, such as by the means 25 and said block is provided with through transverse ports 26 and 27 and a blind transverse port 28. The wall bounding the transverse ports aforesaid is enlarged in diameter at 29, and said enlarged diameter portions are adapted to receive ends of tubes 30, 31 and 32. The opposite end of the tube 31 is anchored within a bore 33 of fitting 34, the said fitting being secured to the bulb 17, so that the tube has communication with the interior of said bulb. The tube 32 is reversibly curved at 35, and is anchored within a bore 36 of fitting 15 so that the end of the tube has communication with the space 21 of the fitting.

Screw-threaded connectors, designated generally as 37, are received in threaded openings of

the block 24, concentric with the various ports 26 and 27, as shown in Figure 1. These fittings permit connection with the source of liquid supply, the specific gravity of which is to be recorded. The tube 32 is in communication with port 38, which is at right angles to port 28 in block 24 to form therewith an elbow-shaped passage, and the wall of the block concentric with the port 38 is threaded to receive a fitting 39. This fitting is adapted to have secured thereto in any appropriate manner a tube 40. This tube has the opposite end thereof communicating with the interior of a thermostat casing 41. The tube 30 also has communication with the interior of the same casing 41 (see Figure 3). The thermostat and its casing are supported by member 42, the member 42 being movably or slidably fastened to the base 1. Within the casing 41 is tube 43. One end of the tube is internally threaded at 44, and closed by means of a cap nut 45. The opposite end of the tube is provided with an enlarged head 46, which is shouldered and screw-threaded at 47; whereby said tube may be threaded within an opening 48 of the casing 41. The head is formed with a bore, which may be bushed or otherwise constructed so as to provide a bearing for a short shaft 49. This shaft has an end received within the tube 43, which end has fastened thereto one end of a thermostat coil 50. This coil may be formed of bi-metal material, such as brass with an overlay of Invar metal. The opposite end of the coil is fastened to a short stud 51 carried by a screw cap 45. Secured to the outer end of the shaft 49 so as to be rotated upon a turning of said shaft is a lever 52. This lever includes a short arm 53 having an enlarged end 54 adapted to be carried on the shaft 49 and locked to said shaft by means 55. The arm 53 directly communicates with a part 56 at right angles thereto and the part 56 in turn is connected to part 57 which is substantially parallel with the arm 53. The reason for providing a lever having a returnedly bent and spaced end portion will appear as the description proceeds.

Secured to the member 4 is an arm 58, the end of which is provided with a bearing 59 adapted to house a short shaft 60. Secured to the shaft is lever 61 and this lever in turn has secured thereto a floating lever 62 as by pivot means 63. A link 64 provided with pinned adjustable slide blocks 65 and 66 is interposed between the counter-balance beam and the floating lever.

A link 67 provided with pinned adjustable slide blocks 68 and 69 is interposed between the floating lever and the lever 52. The movable or slidable relationship of the member 42 with respect to the base may be effected in any suitable manner in order to permit adjustment of the link 67 and its slide blocks 68 and 69 to the right and left of the limiting positions imposed by the length of the lever 52. Such movement of the member 42 may require flexure or adjustment of the tubes 30 and 40.

In the adaptation of the invention, I have found it expedient to use some indicator which properly records any rise and fall of the bulb 17 when the instrumentality as an entirety is properly calibrated for the particular gravity of liquid under test. To this end, I indicate at 70 a chart of the usual type which is clock operated and over the face of which is adapted for movement a pen arm 71. One end of the pen arm is keyed to the shaft 60.

Also, it may be desired that the said device operate other instrumentalities in accordance with movement of the bulb 17 and I have roughly indicated suitable means, which includes an arm 72, one end of which is keyed to the shaft 60, and the opposite end of which is provided with valve discs 73. A bracket 74 supports a block 75 provided with ports 76 and 77, ends of the ports opening outwardly of the block in the zone of the spaced valve discs 73. Dependent upon movement of the arm 72, one or the other of the ports will be open to the atmosphere. Suitable tubes 78 and 79 communicate with the block and with the ports 76 and 77. If compressed air is not used for the medium for moving certain other apparatus, dependent upon movement of the lever arm 72, I may provide the electrical switch means shown at 80, wherein a pair of spaced contacts 81 and 82 are carried on an insulation block 83. The arm 72 carries a member 84 which may be brought into engagement with one or the other of the contacts, depending upon direction of rotation of the arm 72. Electrical connections are made with the contacts and with the member 84.

The operation, uses and advantages of the gravimeter just described are as follows:

Referring to Figure 1, it is necessary that the bulb 17 adapted to receive the liquid, the specific gravity of which is to be recorded, should be of a size so that a sufficient quantity of liquid may be received therein to give a deflecting force, which is measurable on the chart 70 when the pen arm 71 moves thereover. The gravimeter is adapted to operate with a moving fluid. In other words, suitable connection is made with the connectors 37 which join the pipes or tubes 30 and 31, whereby the continuously moving sample will move through the tube 31 into the bulb 17 and substantially fill the same. This liquid will flow into the tube 20, as indicated by the arrow, thence fill the space 21, through tubes 32, 40 into the casing 41 within which is positioned a thermostat, out of said casing into tube 30. The direction of flow is indicated by the arrows. Some standard is utilized for the liquid, which as I have before stated, may be 60° F. At 60° F., the apparatus is so adjusted that the minimum density of a liquid at this temperature will not produce any deflection of the beam 1. Thus, in calibrating the instrument, I calibrate it for the specific gravity of the liquid under test at a given temperature. By way of example, I move the counter-balance weight 23 on the counter-balance beam so that the weight of the bulb, its contents and its associated elements are perfectly balanced and the tubes 31 and 32 are in transverse stress, that is to say, tend to raise the bulb 17. The adjustment of the weight 23 is such with relation to the adjustment of the tubes 31 and 32 that when the density of the liquid within the bulb is at the minimum point desired as a basis for the record, the counter-balance weight 23 will just sustain the bulb in its position with a very small initial flexure of the resilient tubes. If now the density of the liquid flowing into and out of the tubes should increase, the bulb 17 is depressed, the counter-balance weight 23 offering no resistance to movement of the bulb as the system is in balance, and such resistance as is offered being that of the tubes 31 and 32. This depression of the bulb will cause a movement of the indicating arm 71 to record, by the pen connected with said arm, a suitable line on the face of the chart 70. This

movement will be in direct proportion to the change in density of the continuously flowing sample. If we assume now that the liquid is not at the standard base temperature at which its gravity is employed in calculation or adjustment of processes, the temperature above or below the standard point will cause, through the action of the coil of the thermostatic metal 50 movement of the lever 52, which movement will act to move the link 67 and thence act on the intermediate point or zone of the floating lever 62. For instance, if the temperature increases, the thermostat coil 50 will rotate the shaft 49 in a clockwise direction to in turn move the right end of the lever 52 downwardly, which in turn will move the floating lever in a clockwise direction with respect to shaft 60 or in other words, downwardly, viewing Figure 1. This downward movement of the floating lever will produce a movement of the lever 61 and thereby the pointer or recording pen which will adjust it to a position on the chart 70 corresponding to the true density of the liquid sample at the standard base temperature.

Viewing Figure 1 and the position of the apparatus as shown, if the standard sample has been calibrated for a certain density, it is evident that the link 67 will not move as the thermostat will maintain the arm 52 in a given position, say that illustrated. Hence the density of the flowing sample is all that will affect the beam 7. The floating lever will then be held by the link so that any movement of the lever will be about the connection 68, acting as the fulcrum. Movement of the floating lever is, of course, accomplished through the medium of the link 64 and its connection between the counter-balance beam and the floating lever. Thus, if the counter-balance end of the beam rises, that portion of the floating lever outward from the fulcrum point, assumed to be the block 68, will rise and depress the opposite end of the floating lever where it has connection, as at 63, with a lever 61. Movement of the lever 61 will actuate the pen arm 71 in a clockwise direction. If the density of the sample should be lighter, the bulb will rise for the reason that initially a given sample fills the said bulb, which sample plus the bulb and connections have been counter-balanced by the weight 23. Thus, if the sample has a lesser specific gravity than that for which it has been set, the beam will tend to rotate clockwise, and in so doing, will move the floating lever in a clockwise direction about its fulcrum point with the block 68. This will move the lever 61 in an anti-clockwise direction relative to shaft 60 and will move the pen arm 71 anti-clockwise. If now the temperature of the sample should vary, say become a temperature less than 60° F., the lever 52 would move in an anti-clockwise direction, viewing Figure 1, and move the link 67 upwardly and move the floating lever also upwardly, but specifically so that the floating lever would move in an anti-clockwise direction relative to its connection 63 with lever 61. Thus, temperature is automatically compensated.

In order that there may be no possibility of accumulation of gas in the upper part of the bulb or an abnormally heavy liquid, such as water, in the lower part of the bulb, it is to be observed that the lower end of the induction tube 20 is placed close to the bottom of the bulb so that any abnormally heavy liquid which accumulates will be drawn out by movement of the normal sample through the induction tube to discharge. The ports 22 at the top of the bulb will aspirate therethrough any gas or air contained in the upper part

of the bulb through the tube 32 and be discharged from the instrument.

In order to employ the gravimeter in the control as well as the indicating or recording of specific gravity, electrical contacts illustrated may be positioned so that the arm 72 may bring the portion 84 into one or the other of the contact points 82, 83 to actuate, through a relay, or other device, appropriate mechanism within a determined range or density of the liquid. I may also use the frictionless type of pilot valve, illustrated in Figures 1 and 2, which may control the opening or closing of compressed air, or other fluid, for the purpose of operating auxiliary apparatus to control the specific gravity of the liquid. Various controls will readily suggest themselves to those familiar with the art to which this apparatus appertains.

Particular attention is called to the fact that the tubes 31 and 32 are formed of spring-like material and act as a spring-balance for the bulb after the bulb and associated parts have been balanced through the weight 23 on the beam. This is important for the reason that any change in density of the liquid received in the bulb during its flow will deflect the tubes. Thus, the device is very sensitive and a minute deflection of the tubes is immediately indicated on the chart 70 by a pen or other device carried by the arm 71.

Under certain circumstances, it may be desired that movement of the thermostat produce no deflection in the link 67. This is conveniently accomplished by sliding the blocks 68 and 69 along the floating lever 62 and the lever 52. The link 67 should at all times be maintained in a vertical position. The flow of liquid within and outwardly of the bulb does not affect the correct operation of the device as an entirety. It will be observed that all dynamic force of moving liquid is absorbed within the tubes 31 and 32. This is important for accuracy of operation of the device and is one of the features of the present invention.

I claim:

1. In a liquid gravimeter, a pair of resilient tubes, a relatively fixed support for one end of each of said tubes, and a bulb secured to and partially supported by the opposite ends of said tubes; one of said tubes serving to conduct a flowing liquid into the bulb and the other of said tubes providing for the egress of liquid from the bulb; a counter-balance beam cooperating with said tubes for supporting the bulb in every position when filled with liquid of a selected specific gravity, means for balancing said beam, bulb and its contents and stressing said tubes at said selected specific gravity whereby change in specific gravity and liquid flowing through said bulb, produces deflection of said tubes, and means to indicate said deflection.

2. In a liquid gravimeter, a pair of spring tubes, a relatively fixed support for one end of each of said tubes, a bulb partially supported by, secured to and interiorly communicating with said tubes to allow a liquid sample to flow continuously through one tube into said bulb and outwardly discharge through the other tube, adjustable balance means cooperating with said tubes to support said bulb in every position, and means for recording deflection of the tubes due to change in specific gravity of the liquid sample received in said bulb.

3. In a liquid gravimeter, a bulb adapted to receive a liquid, adjustable means for counter-balancing the weight of the bulb and its contents in every position, a pair of spring tubes leading to

the interior of said bulb through which tubes a liquid sample has continuous ingress and egress with the bulb, said tubes cooperating with said counter-balancing means to support said bulb, and means for recording deflection of the tubes due to change in specific gravity of liquid sample flowing through the bulb.

4. In a liquid gravimeter, a floating lever, a bulb suspended for vertical movement adapted to receive a continuous stream of liquid passing therethrough, resilient conduits partially supporting said bulb and communicating therewith for the passage of said liquid, balance means of connection between the floating lever and said bulb whereby a change of density of liquid within the bulb produces movement thereof and of said floating lever and balance means, a thermostat responsive to the temperature of said liquid, and means of connection between the thermostat and the said floating lever whereby change of temperature of liquid within the bulb will actuate the thermostat to move the floating lever, and a recording device secured to the floating lever.

5. In a liquid gravimeter, a bulb, an ingress tube and an egress tube for a sample liquid communicating with the interior of said bulb, said tubes being resilient for lending support to said bulb, means cooperating with said tubes for counter-balancing the bulb and the liquid within said bulb, a thermostat within the flow path of the liquid sample passed through said tubes, a lever adapted to be moved by movement of said thermostat due to change of temperature of said liquid, a floating lever, a link connection between said floating lever and the counter-balancing means, a link connection between the thermostat lever and the said floating lever, and a recording pen arm swingingly secured to an end of said floating lever, whereby change of density of liquid flowing through said tubes and said bulb acts as one force, and temperature change producing movement of the thermostat lever acts as the other force producing movement of said pen arm corrected for actual temperature of the liquid so that the density recorded is that of the liquid as of the standard base temperature.

6. In a liquid gravimeter adapted to indicate the specific gravity of a liquid as of a standard temperature; a pressure chamber member adapted to receive the sample liquid, resilient means lending support to said member whereby the sample liquid may be conducted in a continuous flow path to and from said pressure chamber member, counter-balance mechanism cooperating with said means for supporting the pressure chamber member when filled with the sample liquid, a floating lever, means of connection between said lever and the counter-balance mechanism, an indicator pointer shaft, an intermediate connection between the said shaft and an end of said floating lever, a thermostat included within the path of the flowing sample liquid, and means for transmitting motion of the thermostat due to changes of temperature of the liquid to said floating lever.

7. In a liquid gravimeter, a bulb, a counter-balance beam for balancing the weight of the bulb and any content therein, means cooperating with said beam in the support of said bulb for conducting a liquid sample within said bulb, means for conducting a liquid sample from the bulb, an induction tube within the bulb and through which the liquid must pass in its flow through the means aforesaid, means cooperating with said tube to remove entrapped air from said bulb, change in specific gravity of the liquid sample shifting the counter-balance beam, and means for recording movement of the beam to indicate change in specific gravity of the liquid.

8. In liquid gravimeter construction, a bulb, the interior of which acts as a pressure chamber for a liquid, fluid connections for promoting circulation of fluid through said bulb, an induction tube within the bulb through which the liquid in the bulb must pass in any flow movement, said induction tube extending to the upper portion of said bulb, and means defining ports near the upper portion of said bulb cooperating with said induction tube for aspirating any gas above the liquid in said bulb resultant upon passage of liquid through the induction tube.
